UNITED STATES PATENT OFFICE.

WILLIAM DIETER, OF NEWARK, NEW JERSEY.

AUTOMOBILE TORPEDO.

Original application filed July 15, 1925, Serial No. 43,791. Divided and this application filed September 14, 1926. Serial No. 135,495.

This invention relates to torpedoes of which the standard Bliss-Leavitt torpedo is an example, in which compressed air from a flask or reservoir is passed at reduced pressure through a heater or so-called superheater in which a combustible such as alcohol is burned, and into which atomized water is sprayed and the resulting mixture of combustion gases and steam is discharged through a nozzle against the buckets of a turbine by which the torpedo is driven.

The invention relates to means for controlling the speed of the torpedo. Heretofore the speed control has been accomplished by adjusting the pressure reducing valve so as to discharge the air at greater or less working pressure. It has also been proposed to provide two or more superheaters or fire pots and to provide valves for controlling the flow of compressed air, fuel and water into the respective pots, admitting these to one only for low speed, or to two for higher speed; or with three pots, to all three for the highest speed.

The present invention provides for gaining a wide range of speed adjustment by a substantial duplication of the usual superheating pot and its accessories, including the reducing valve through which the air is fed to such pot. This admits of introducing air at low pressure into the first pot, and at high pressure into the second pot, whereby to give two sufficiently different speeds; or by simultaneously admitting to both to give a third and highest speed.

The invention provides also certain features of mechanism whereby to accomplish these desirable results.

The present application is a division of my application filed July 15, 1925, Serial No. 43,791.

The preferred embodiments of the invention are shown in the accompanying drawings, wherein,

Figure 1 is a schematic view, being a fragment of the mid-section of the torpedo shown in vertical longitudinal mid-section, with the reducing valves, superheater pots and their accessories arranged in a single plane, so that their working connections may be traced.

Fig. 2 is a vertical mid-section through the valve J of Fig. 1.

Figs. 3 and 4 show a means for controlling the flow of air, whereby at launching to

drive through one power system, and at any desired time after launching to drive also through the other; Fig. 3 being a vertical section of the parts concerned, and Fig. 4 being a horizontal section on the line 4-4 in Fig. 3.

Fig. 5 is a fragmentary elevation showing certain of the parts in Fig. 1, with a modified means for accomplishing the same results as with the device of Figs. 3 and 4.

Fig. 6 is a fragmentary diagram showing a modification of Fig. 5.

Figs. 3, 4 and 5 herein referred to are some of the figures in my aforesaid application Serial No. 43,791.

Referring first to Fig. 1, the torpedo is shown at A and a fragment of the launching tube at B. The torpedo A has the usual compressed air flask C, from which as usual leads a compressed air conduit a that conveys the high pressure compressed air to the inlets to two valve structures D D' each of the usual construction in this type of torpedo, that is to say, including a starting valve b and a pressure reducing valve c, from the latter of which a conduit d leads air at reduced pressure to the inlet of the corresponding combustion or superheater pot E or E' from the outlet of which conduits e e' respectively lead the mixed combustion gases to two turbine nozzles f and f' respectively which discharge into the buckets of a turbine wheel F. This turbine F is shown schematically as being a single wheel, being mounted directly on a propeller shaft Q; but this arrangement may be varied according to any standard or suitable construction of turbine propulsion.

As the valve structures D D', heaters E E' and their accessories are duplicated throughout, it will suffice to describe one of these systems, the corresponding parts in the other system being marked with the same letters with the addition of prime (') marks.

From the high pressure side or chamber g of either or each reducing valve is led a duct h which carries high pressure air to spin up the gyroscope. As this has no relation to the present invention the course of this duct is not illustrated.

From the high pressure side of the reducing valve there also leads an air duct which divides into two branches j and m which convey high pressure air respectively to an air stop valve G and a liquid stop

valve J. These valves normally or before launching shut off the water chamber or reservoir H and the fuel chamber I from communication on the one hand with the source 5 of air at working pressure, and on the other hand with the spray nozzles in the heaters; the purpose and general operation of such valves is set forth in the patent to F. M. Leavitt, No. 1,022,486, dated April 9, 1912. 10 In that patent, however, the valves are operated at working pressure or from the low pressure side of the reducing valve, whereas, I now prefer to provide for operating the valves by high pressure air from the reservoir side of the reducing valve. This feature, however, is not claimed in my present application, but is made the subject of another application, Serial No. 52,383, filed 15 August 25, 1925.

20 In Fig. 2 the valve J is shown in section. The air pressure pipe m enters at the bottom beneath two plungers 7, 7, above which are the stems of check valves 8, 8 which are normally pressed down to their seats by 25 springs 9, 9. The valve J is a double valve, one side controlling water, and the other side alcohol or other liquid fuel. When the starting valve is opened, high pressure air flows through the duct m and lifts the 30 plungers 7 and unseats valves 8. This establishes communication from the fuel chamber I through duct n to the valve, and thence by a duct p to the fuel inlet nozzle q of the heater E; simultaneously it establishes communication from the water tank 35 H by duct r to the valve J, and thence through duct s to the water spray nozzle t of the heater E.

The valve G is constructed essentially 40 like the valve J. The admission of high pressure air through duct j opens in like manner the internal check valves and thereby establishes communication between an air duct i leading from the low pressure 45 side of the reducing valve, and the water and fuel vessels, so that air at working pressure is admitted through duct k to the top of the water vessel H and through duct l to the top of the alcohol vessel I.

50 By the utilization of high pressure air for controlling the valves J and G and their counterparts J' and G', these respective valves are operated with great positiveness, and for holding them closed in their dormant condition the springs 9 which seat the check valves 8 may be made stiff springs holding the valves closed positively against the possibility of leakage. As the description proceeds it will be apparent that this 55 positive action of the respective valves enables the operation to be confined to one or other of the power generating systems, thereby making the apparatus selective with great certainty of action.

60 The starting valve b is of the type which

is standard in the Bliss-Leavitt torpedoes, being a differential plunger valve normally receiving high pressure air above it (by leakage past it from the conduit a) to keep it closed until this pressure is relieved 70 through a vent u controlled by a vent valve w operated by a launching trigger v through a lever x. At launching the trigger encounters an actuating stop K projecting within the launching tube, whereby the trigger is thrown back and the valve w opened to vent the starting valve, whereupon it is opened by the high pressure air beneath it; all as is the well-understood 75 operation in such torpedoes.

In duplicating the valves and heaters and their accessories they may, for example, be arranged in the manner shown in Fig. 1. In any event the high pressure air conduit a branches into the inlets of both valves D 80 D'. From this point on each of the duplicated systems is of precisely the standard construction until the outlet conduits e e' for motor fluid and their respective nozzles f f' are reached. Each of these nozzles may be 85 of the standard construction but the two are arranged to discharge into the turbine at points suitably removed from one another, say, for example, about 90° apart. While the two reducing valves might be set to 90 deliver the air at the same pressure, yet it is preferable and one of the advantages of the present invention that they may be set for widely different pressures. This setting is 95 accomplished in the conventional way by a screw adjustment determined by means of what are called "speed rings", as set forth in my Patent No. 1,131,341, dated March 9, 100 1915. In Fig. 1 the speed rings are shown at y y' respectively.

105 Assuming the pressure valves to be set for different pressures, let us assume that the pressure of D is such as to generate fluid in the heater E adequate to maintain propulsive power at the rate, for example, 110 of 80 H. P., and that the setting of the other valve c' is such as to cause the generator E' to discharge fluid at a rate such as to maintain propulsive energy at, for example, 115 H. P. With such relative adjustments three 120 powers and consequently three different 125 speeds for the torpedo are available. For low speed E alone may be used. For an intermediate speed E' alone may be used. For the highest speed both may be used 120 conjointly, giving 200 H. P.

The foregoing description is substantially identical with that in my said application No. 43,791; in that application provision is made for actuating at launching either or both the valves w controlling either or both the starting valves b b', so as to give any one of the three speeds thus attainable.

130 My present invention provides for the exercise of the respective powers in succession

rather than simultaneously. For this purpose the construction shown in Figs. 3 and 4 may be applied.

Referring to Fig. 3, the trigger *v*, lever *x* and vent valve *w* are the same as the correspondingly lettered parts in Fig. 1, and the valve *w* controls the starting valve *b* of the valve *D'* and heater *E*. The valve *w* here shown in dotted lines is of conventional construction. In immediate proximity to it is a second vent valve *w''* of like construction which is connected by a duct *u'* to the chamber of the starting valve *b*. The valves *w* *w''* have each the usual plunger 6 which when elevated is locked by a bolt 7 which springs under it impelled by a spring 8 so as to hold the valve open during the run of the torpedo. The valve *w''* has the plunger 6 prolonged downwardly as a pin 9, the lower end of which is in position to be struck by the toe 10 of a cam which is adjustably connected to a wheel 11 of the reducing or timing gear called the "distance gear" of the torpedo, and which is driven from a propeller shaft *Q* through a worm 13 thereon, driving a worm wheel 14 carried on an upright spindle 15 which has a worm 16 meshing with the gear 11 and also with the gear 17, which latter is connected in the usual manner to the stopping means (not shown) for closing the starting valve and shutting off air to stop the torpedo. The cam 10 is to be turned to a suitable setting before launching so as to determine the time interval between the starting of the torpedo under the power generated in the heater *E* alone and the opening of the vent *w''* to determine the turning on of additional power through the heater *E'*. For this purpose the cam 10 may be frictionally connected with the gear 11 and mounted on a spindle 18 which may extend to the exterior of the torpedo and be provided with suitable setting means as usual with torpedoes for indicating the proper setting positions for any given time interval.

Before launching, the cam 10 will be set rotatively by turning the spindle 18 to correspond to the number of yards to be run before the second power system is rendered active. At launching, the hook *v* is pulled and the vent *w* operated to open the starting valve *b* and start the torpedo with the power generated by the primary heater *E* alone; after running the prescribed number of yards the cam 10 lifts the pin 9, opens the vent *w''* and thereby opens the starting valve *b'* and thereby turns on the power generated in the secondary heater *E'*; thereafter the torpedo runs under the sum of both power systems until the end of its run.

Fig. 5 shows a modified means for starting either the primary or secondary power

systems. Instead of the means shown in Figs. 3 and 4 a vent valve *w'''* is provided 65 which is connected to the starting valve *b* or *b'*. Projecting through the hull is a fin *L* which is connected to a cam *M* which normally in the position shown arrests a lever *N* connected to the plunger 60 of the valve 70 *w'''* and holds it closed. Upon launching, the water on striking the fin *L* throws it backward so that the toe of the cam releases the lever *N* and permits the valve to open under stress of a spring 20. This device can be used (by connecting the parts as shown in Fig. 6) in lieu of the trigger *v* of Fig. 3 for starting the primary power system, leaving the secondary power system to be started through a timing mechanism 75 as shown in Fig. 3; or the primary power system can be started as in Fig. 3 through the action of the starting hook or trigger *v* and the secondary system can be started by the action of the fin *L*; this being the arrangement shown in Fig. 5.

It will be apparent to those skilled in the torpedo art that the devices herein illustrated, which are the best known to me for carrying my invention into effect, may be varied or modified without departing from the spirit of the invention as herein set forth and defined in the appended claims.

What I claim is:

1. In a torpedo having a compressed air flask and propelling mechanism, dual power generators each comprising a reducing valve, a heater, means for feeding fuel and water to the heater, and a discharge from the heater to the propelling motor, with controlling means adapted to admit compressed air to one of the power generators in advance of the other. 95

2. In a torpedo according to claim 1, the controlling means having timing means for delaying the admission of compressed air to the power generators which is later operated. 105

3. In a torpedo having a compressed air flask and propelling mechanism, dual power generators each comprising a starting valve, a reducing valve, a heater, means for feeding fuel and water to the heater, and a discharge from the heater to the propelling motor, with controlling means adapted to open the starting valves in succession, whereby to admit compressed air to one of the power generators in advance of the other. 110

4. In a torpedo according to claim 3, the controlling means having timing means for delaying the admission of compressed air to the starting valve which is later opened. 120

In witness whereof, I have hereunto signed my name.

WILLIAM DIETER.
